(57) **CLAIM**

The ornamental design for a vehicle wheel, as shown and described.

DESCRIPTION

FIG. 1 is a front top right perspective view of a vehicle wheel according to our design;

FIG. 2 is a front elevation view of the vehicle wheel of FIG. 1; FIG. 3 is a top plan view of the vehicle wheel of FIG. 1, a bottom plan view being a mirror image thereof;

FIG. 4 is a right side elevation view of the vehicle wheel of FIG. 1, a left side elevation view being a mirror image thereof; FIG. 5 is a cross-section view of the vehicle wheel of FIG. 1 taken along the line 5-5 in FIG. 2; and,

FIG. 6 is a cross-section view of the vehicle wheel of FIG. 1 taken along the line 6-6 in FIG. 2.

The broken line showing of the rear of the rim is included for the purpose of illustrating environment and forms no part of the claimed design. The dot-dashed lines that define the bounds of the claimed design form no part thereof.
